United States Patent Office.

GEORGE R. MOORE, OF PHILADELPHIA, PENNSYLVANIA.

Letters Patent No. 97,105, dated November 23, 1869.

IMPROVEMENT IN WATER-CLOSETS.

The Schedule referred to in these Letters Patent and making part of the same.

I, GEORGE R. MOORE, of the city of Philadelphia, county of Philadelphia, in the State of Pennsylvania, have invented certain new and useful Improvements in Water-Closet Hoppers, of which the following is a specification.

The nature of my invention consists of an improved form and construction of the water-closet hopper, with regard to the adaptation of the cover and trunk to each other, in such a manner as to afford suitable bearings for the pan-shaft upon the same castings, and without any other fitting; also, to bring the joint between the cover and the trunk at the top, where it is least of all objectionable, and where it will be covered, and a tight joint made with the putty ordinarily used in setting the earthen basin, while the cover, withal, closes direct, and is secured firmly and cheaply by simple screws; and all this without increasing the difficulty of moulding.

I keep the form of the trunk such, in every respect, that it can be readily moulded in an ordinary two-part flask, which is quite an advantage to the manufacturer.

Figure 1 is a side view of the hopper with the cover in its place.

Figure 2 is a perpendicular middle section.

Figure 3 is a top view with the cover in its place.

Figure 4 is a top view of the trunk with the cover removed.

A is the trunk.

B is the cover.

a a a are lugs cast inside the trunk, and receive the screws for holding down the cover.

It will be seen that the cover makes a joint upon a slight shelf in the trunk made to receive it; also, that suitable bearings for the pan-shaft, at b, are cast in the metal, the lower half upon the trunk, and the upper on the cover, at c, so that when the cover is off, the pan-shaft can be lifted out conveniently.

The lower part of the trunk has branches d d d, for fastening it up in the usual manner.

E is a shelf for a valve.

F is a lug for attaching a suitable lever.

Having thus fully described my invention, what I claim therein as new, and desire to secure by Letters Patent, is—

The water-closet hopper, having a removable cover, with suitable lugs to rest down perpendicularly upon the pan-shaft, which is journalled in the sides of the hopper, while at the same time the cover fits within the top part of the trunk, so as to bring the joint between them and the top, substantially in the manner and for the purpose herein set forth.

GEO. R. MOORE.
